UNITED STATES PATENT OFFICE.

ALBERT BROADMEYER, OF HARRISBURG, PENNSYLVANIA, ASSIGNOR TO THE W. O. HICKOK MFG. CO., OF HARRISBURG, PENNSYLVANIA, A CORPORATION OF PENNSYLVANIA.

SHEET-FEEDING APPARATUS.

Application filed October 8, 1924. Serial No. 742,402.

In sheet feeding machines of the type in which a vertically movable pile supporting table is employed, it has been the custom to control the operation of the table-elevating means by a controller that rests on the rear end of the pile of sheets at a point distant from the sheet delivering means. It is very desirable that the sheet delivering means be located at a predetermined distance from the top of the pile in order to obtain the best delivering action. However, the sheets are often distorted, buckled or warped, and consequently the surface of the pile that is beneath the delivery device varies in its distance from the delivery device when the controlling element rests upon the end of the pile opposite to that directly operated on by the sheet delivery device. One of the primary objects of the present invention is to provide a mechanism that will have its controlling member adjacent to the sheet delivery device, so that the surface acted on by the latter will always be in substantially the same horizontal plane as that engaged by the governing element.

In the accompanying drawings,

Figure 1 is a side elevation of a feeding apparatus equipped with the novel structure,

Figure 2 is a top plan view of the same,

Figure 3 is a vertical sectional view on an enlarged scale and taken substantially on the line 3--3 of Fig. 2,

Figure 4 is a detail sectional view showing the mounting of the driving cam,

Figures 5, 6 and 7 are diagrammatic views illustrating the unchanging position of the governing element, irrespective of the character of the surface of the pile from which the sheets are fed.

In the embodiment disclosed, a suitable frame 8 is employed, in which is slidably mounted a vertically movable sheet-supporting table 9. This table is engaged by vertically disposed threaded shafts 10 carrying beveled gears 11 at their upper ends. Said beveled gears are in mesh with other beveled gears 12 carried by a horizontal shaft 13 that projects from one side of the bracket and is provided on its projecting end with a ratchet wheel 14. An arm 15, pivoted on the shaft 13, is provided with a pawl 16 adapted to engage the teeth of the ratchet wheel 14, and effect a step-by-step rotation of the ratchet wheel when the arm 15 is swung.

The rotation of the ratchet wheel, in turn, effects the rotation of the shaft 13, and through gears 11 and 12 causes the rotation of the shafts 10, to thereby elevate the table 9, in a manner well understood.

Carried by outstanding horizontal arms 17 of the frame 8 are spaced head plates 18, and extending across the space between said head plates and over the front end of the table 9 is a shaft 19.

Mounted on this shaft is a sheet delivery device, preferably in the form of a suction roller 20. This roller may be of the type disclosed in, and covered by, my former Patent, No. 1,494,303, May 13, 1924, and no further detailed description and showing of the same is believed to be necessary in connection with the present invention. The shaft 19, which may be considered the driving shaft of the apparatus, projects beyond the head plate 18 on the side of the machine 75 having the ratchet wheel 14 and pawl 16, and journaled on said projecting end of said shaft is a driving cam 21. Said head plate also has a guide box 22 in which is slidably mounted an actuating plunger 23 having a 80 roller bearing 24 on the upper face of the cam 21. This plunger 23 is also preferably provided with a loop portion 25, in which is engaged the end of the shaft 19, said loop portion and shaft thus acting as a guide for 85 the upper end of the plunger. Mounted on the lower end of said plunger is a coiled spring 26 that bears against the lower end of the box 22 and against a collar 27 fixed upon the lower end of the plunger and serving to move the plunger downwardly after its elevation by the cam 21. A bell crank lever 28 is fulcrumed at 29 on the headplate 18, and one arm 30 thereof has a slotted engagement 31 with a pin 32 carried by the 90 plunger. The other arm 33 of the bell crank is slotted, and in said slot is engaged the pivot 34 of a link 35 that is pivoted, as shown at 36, to the lower end of the pawl-carrying arm 15.

Located at the delivery side of the suction roller 20 is a conveyer, comprising an endless belt, a portion of which is shown at 37, and this belt passes around a roller 38. The roller is driven from the shaft 19 by a 105 train of gears 39 extending from said shaft, to the roller at the rear side of the apparatus. The front end of the roller 38 is oper-

atively connected to the cam 21 through a train of gears 40, the gear trains being such that the cam 21 will be rotated at less speed (preferably half) than the speed of the 5 shaft 19 and consequently of the suction roller 20.

The plunger 23 has fixed thereto an offset stop lug 41 adapted to be engaged by a hooked latch 42, pivoted at 43 on the head 10 plate 18, said latch being movable to a position beneath the lug 41 to prevent the dropping of the plunger and consequently the active operation of said plunger. A rock 15 shaft 44, journaled in the head plate, carries a depending arm 45, in the lower end of which is engaged a link 46, and this link has a loose play connection 47 with the latch 42. Preferably an adjustable weight 48 is mounted on the rock shaft 44 and serves to 20 swing the arm 45 and link 46 outwardly so that the latter will be in position to move the latch 42 from beneath the lug 41. The rock shaft 44, as clearly shown in Figure 2, projects inwardly beyond the head plate 25 18, and has secured thereto a governor arm 45^a provided with a terminal ball 46^a adapted to rest on the top of a pile of sheets placed on the table 9 at the front end of 30 said pile, and preferably in substantial alignment with the suction roller 20.

The cam 21, as shown in Figure 4 is fixed to a sleeve 21^a journaled on the shaft and in the head plate 18. On the inner end of this sleeve is fixed an oppositely disposed cam 21^b on which rides a roller 21^c carried by an arm 21^d that is fixed in turn to the rock shaft 24. This cam 21^b, acting on the arm 21^d and thereby on the rock shaft 44 serves to periodically ease the weight of 40 the parts on the paper pile.

The operation of the apparatus is as follows: Assuming the shaft 19 is being rotated and the suction roller in action, it will be evident that said roller will remove sheets 45 successively from the top of the pile and deliver them to the conveyer 38, this conveyer operating synchronously with the shaft 19, and in turn driving through the train of gears 40 the cam 41 at about half 50 the speed of the roller 20. As said cam 21 rotates the plunger 23 will be alternately elevated and released to permit the spring 26 to move it downwardly. Assuming that the latch 42 is out of the path of the lug 41, 55 a downward movement of said plunger swings the bell crank into position to move the arm 15 rearwardly and cause the pawl 16 to pass over one or more teeth of the ratchet wheel 14. As the cam continues to 60 rotate, the pawl will engage behind one of the teeth, thereby causing a partial rotation of the ratchet wheel 14, the shaft 13 and the screw shafts 10. This will effect a slight elevation of the table 9 and of the pile of 65 paper thereupon. This upward movement

will be continued until the top of the pile swings the controller arm 46 sufficiently to permit the hooked latch 42 to move beneath the lug 41, whereupon the plunger 23 will be prevented from dropping and the elevation of the table will be stopped. As soon as a sufficient number of sheets have been delivered from the top of the pile by the roller 20, the arm 45^a dropping will cause the latch 42 to be again moved from beneath the lug 41 and another elevating operation of the table will take place.

The arrangement disclosed is important for the following reasons. As already stated it is desirable that the suction roller 80 20 be maintained at a predetermined distance from the top of the pile of sheets in order that the feeding action will be most effective. By referring to Figures 5, 6 and 7, it will be noted that with the present 85 structure this distance will be substantially maintained, irrespective of the character of the sheets in the pile. Thus in Figure 5, the pile of sheets A is shown as having their front ends upturned, making the front end 90 of the pile thicker than the rear portion. The governor, 46, resting on the front end of the pile, maintains said end at a predetermined distance from the roller 20. The next pile, or it may be a portion thereof, is shown 95 in Figure 6 as being of sheets B absolutely horizontal. The front end thereof beneath the suction roller 20 is maintained at the same distance from the roller as in Figure 5, while the rear portion of the pile, it will 100 be noted, will be substantially higher than a pile of the formation shown in Figure 5. If a controller were used therefore that rested on the rear portions of the piles, obviously the sheets in Figure 5 would be much 105 closer to the suction roller 20 than when the pile was of the formation shown in Figure 6, and with the present structure this difference is obviated. The same is true in the formation shown in Figure 7, wherein 110 the pile of sheets C is thinner at the front end beneath the suction roller 20 than at the rear end. With the present structure the distance is maintained which would not be the case if the governing device were engaged on the rear end of the pile, in which case the surface of the pile beneath the roller would be very much farther away than in either Figures 5 or 6. The provision of means for driving the cam 21 at a 115 slower rate of speed than the suction roller has also been found very desirable for the reason that as the mechanism operates with considerable rapidity, if the cam 21 were fixed to the shaft 19 the upward feed is so 120 sudden that there is a tendency when the surface of the pile is brought up quickly, for the suction roller to take off two sheets 125 at a time. This arrangement materially lessens the possibility of this taking place. 130

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim, is:

1. In sheet feeding apparatus, the combination with a vertically movable sheet supporting table, of means mounted above one margin of the table for removing sheets therefrom, and automatic mechanism for elevating the table including a controlling device having a portion that rests upon the pile of sheets placed on the table, and said portion being located alongside the sheet removing means in substantial line therewith and above the same margin of the table over which said sheet removing means is located.

2. In sheet feeding apparatus, the combination with a vertically movable sheet supporting table, of a rotary suction roller mounted above one margin of the table for removing sheets therefrom, and automatic mechanism for elevating the table, including a swinging controlling arm having a free end that rests upon the pile of sheets placed on the table, said free end being located at one end of the roller in substantial line therewith and above the same margin of the table as the roller.

3. In sheet feeding apparatus, the combination with a vertically movable sheet supporting table, of means for removing sheets therefrom, means for elevating the table, including a reciprocating plunger, a cam for moving the plunger in one direction, a latch for holding the plunger against movement in the other direction, and a device for moving the latch out of position to hold the plunger, said device being located above the table and in the path of a pile of sheets placed thereon.

4. In sheet feeding apparatus, the combination with a vertically movable sheet supporting table, of means for removing sheets therefrom, means for elevating the table, including a reciprocating plunger, a cam for moving the plunger in one direction, a latch for holding the plunger against movement in the other direction, and a device for moving the latch out of position to hold the plunger, said device being located adjacent to the end of the table from which said sheets are removed.

5. In sheet feeding apparatus, the combination with a vertically movable sheet supporting table, of a rotary suction roll above one end thereof for removing sheets therefrom, means for elevating the table, including a ratchet wheel, a pawl operating on the

ratchet wheel, a reciprocating plunger for operating the pawl, and a cam for moving the plunger in one direction, a latch for holding the plunger against an operative movement in the other direction, and a governor arm connected to the latch for moving it to an inoperative position, said governor arm having a free end that is in the path of the end of the pile and the end of the table over which the suction roll is located.

6. In sheet feeding apparatus, the combination with a movable sheet delivering device, of means for presenting sheets in position to be delivered thereby, operating mechanism for said sheet presenting means, including a constantly rotating driving member, and means for constantly moving said sheet-delivering device and rotating said driving member at different rates of speed.

7. In sheet feeding apparatus, the combination with a rotatable sheet delivering device, of means for presenting sheets in position to be delivered thereby, operating mechanism for said sheet presenting means, including a rotatable driving member, and means for constantly rotating the driving member at a lower rate of speed than the sheet delivering device.

8. In sheet feeding apparatus, the combination with a rotatable sheet delivering device, of means for presenting sheets to be delivered thereby, operating mechanism for said sheet delivering device, including a rotary driving member coaxial with the sheet delivering device, and gearing between the sheet delivering device and operating member for driving one at a different speed from the other.

9. In sheet feeding apparatus, the combination with a rotatable sheet delivering device, of means for presenting sheets to be delivered thereby, a shaft on which the device is mounted, operating mechanism for said sheet delivering device, including a rotary driving member loosely journaled on the shaft, and gearing between the sheet delivering device and operating member for driving one at a different speed from the other.

10. In sheet feeding apparatus, the combination with a rotatable sheet delivering suction roller, of means for presenting sheets in position to be delivered thereby, a shaft carrying said roller, operating mechanism for said sheet-presenting means, including a reciprocating operating member, and a cam journaled on the shaft and acting on said member, a conveyer for the sheets including a roller, gearing between the shaft and roller, and gearing between the roller and cam, said gearing effecting the rotation of the shaft and cam at different rates of speed.

11. In sheet feeding apparatus, the com-

bination with a rotatable sheet delivery device, of means for presenting sheets to be delivered thereby, rotatable operating mechanism for said sheet-presenting means, a 5 movable controller for said operating mechanism, rotatable mechanism for operating the controller, and means for rotating said operating mechanism for the sheet presenting means and controller at lower rates of speed 10 than the sheet delivering device.

12. In sheet feeding apparatus, the combination with a rotary driving shaft, of a rotary suction feeding head mounted thereon, means for presenting sheets to said head, 15 operating mechanism for said means, including a movable actuating member, a cam journaled on the shaft for operating said actuating member, a controller latch for holding the actuating member against movement, means for operating the latch includ-

ing a cam fixed to the first cam, and means for driving the cams at a lower rate of speed than the shaft and suction feeding head.

13. In sheet feeding apparatus, the combination with a rotatable suction roller and 25 movable means for presenting a body of sheets thereof, of mechanism for effecting the intermittent movement of said sheet presenting means, including a pawl and ratchet, a swinging arm for controlling the operation of the mechanism by said pawl and ratchet, a rock shaft, an arm carried by the rock shaft and having a portion adapted to rest on the sheets alongside the suction roller, a second arm on the rock shaft, a cam operating on said second arm, and a third arm 30 on the rock shaft having means for operating the swinging controlling arm.

In testimony whereof, I affix my signature.

ALBERT BROADMEYER.

DISCLAIMER

1,632,945.—*Albert Broadmeyer*, Harrisburg, Pa. SHEET-FEEDING APPARATUS. Patent dated June 21, 1927. Disclaimer filed October 11, 1929, by the patentee and assignee, *W. O. Hickok Mfg. Co.*

Hereby enter this disclaimer to claim 13 appearing in the specification of said patent, No. 1,632,945, and which is in the following words, to wit:

“13. In sheet feeding apparatus, the combination with a rotatable suction roller and movable means for presenting a body of sheets thereof, of mechanism for effecting the intermittent movement of said sheet presenting means, including a pawl and ratchet, a swinging arm for controlling the operation of the mechanism by said pawl and ratchet, a rock shaft, an arm carried by the rock shaft and having a portion adapted to rest on the sheets alongside the suction roller, a second arm on the rock shaft, a cam operating on said second arm, and a third arm on the rock shaft having means for operating the swinging controlling arm.”

[*Official Gazette October 29, 1929*]
